ABSTRACT: A video intermediate frequency amplifier is connected to a frequency selective amplifier to amplify the video intermediate frequency signal. The amplified signal is rectified by a diode to form a DC signal after which it is applied through a control dual triode to selected two of three guns of a tricolor cathode-ray tube at the grid electrodes. The DC signal has a magnitude sufficient to put the control triode in its nonconducting state for detuning or correct tuning of the receiver. Thus the cathode-ray tubing produces images having only a single color associated with the remaining gun for detuning or correct tuning.

FIG. 1

FIG. 2

INDICATOR FOR CORRECT TUNING OF COLOR TELEVISION RECEIVER

BACKGROUND OF THE INVENTION

This invention relates in general to color television receivers and more particularly to devices for indicating the resonance in such receivers for correct tuning.

Heretofore, in order to indicate that color television receivers have been correctly tuned, there have been mostly used visual indicators such as electron-ray tubes, tuning point indicating meters, etc. As the color television receivers are devices for originally providing visual informations it is unreasonable and expensive to indicate the correct tuning thereof through the use of such visual indicators additionally provided in the receivers. Moreover the televiwers will feel psychologically uneasy about whether or not the images being developed on the associated cathode-ray screen will have correctly correlated with the particular indication on the indicator leading to the inconvenience that he must repeatedly move his eyes from the image to the indicator and vice versa to compare then with each other with the eyes. In addition, he can not see well the indicator because of its small size.

SUMMARY OF THE INVENTION

Accordingly it is an object of the invention to provide a new and improved device for indicating the resonance in a color television receiver for correct tuning.

It is another object of the invention to provide a new and improved device for plainly indicating correct tuning of a color television receiver with a large area of indication.

It is still another object of the invention to provide a new and improved correct tuning indication device incorporated into a color television receiver and utilizing the associated cathode-ray screen adapted to have produced on the entire area images having only a selected one of the three primary colors upon the receiver having been tuned out or correctly.

With the above cited objects in view of the invention resides in a tricolor television receiver comprising tuning means and a tricolor cathode-ray tube including three guns and a phosphor screen wherein an indication device for indicating the resonance in the receiver for correct tuning is provided including means for causing a variation in color of images produced on the phosphor screen in accordance with a change of the receiver from its detuned to its tuned state and vice versa.

In a preferred embodiment of the invention the indication device comprises a frequency selective amplifier connected to a video intermediate frequency amplifier to amplify the video intermediate frequency signal, a diode connected to the selective amplifier to rectify the output from the latter and a control amplifier having supplied thereto the rectified signal, having a magnitude sufficient to put the control amplifier in its nonconducting state for correct tuning or detuning of the receiver, the control amplifier supplying its output to selected two of the guns at the grid electrodes thereby to drive the selected two guns into their cutoff state for detuning or correct tuning whereby the images produced on the phosphor screen have a single color associated with the remaining gun.

BRIEF DESCRIPTION OF THE DRAWING

The invention will become more readily apparent from the following detailed description taken in conjunction with the accompanying drawing in which:

FIG. 1 is a fragmental schematic circuit diagram of a color television receiver constructed in accordance with the principles of the invention; and

FIG. 2 is a graph useful in explaining the operation of the invention.

Referring now to FIG. 1, there is illustrated a preferred form of the invention and only that portion operatively associated to the invention of a three gun tricolor television receiver of

the conventional construction. The last amplifier stage V_1 of a video intermediate frequency amplifier is electrically coupled to a color matrix comprising three vacuum tubes V_R , V_G and V_B in the manner as well known although it is not illustrated.

5 Those vacuum tubes V_R , V_G and V_B are applied to produce at their anode electrodes color difference signals $R-Y$, $G-Y$ and $B-Y$ respectively where R , G and B represent the actual red, green and blue components and Y represent the luminance signal.

10 The red tube V_R is energized by a source of positive voltage $B+$ through a voltage dropping resistor $R1_R$ and has the anode electrode connected to a parallel combination of a capacitor C_R and a resistor $R2_R$ is, in turn, connected to a grid electrode G_R of a red gun of in a shadow mask type three gun tricolor cathode-ray tube V_C of conventional construction. Thus the tube V_R supplies the color difference signal $R-Y$ to the grid electrode G_R of the red gun. The junction of the $C-R$ parallel combination C_R-R2_R and the grid electrode G_R of the cathode-ray tube V_C is connected to a control resistor $R3_R$ for controlling a color bias. The control resistor $R3_R$ is then connected to a slide on a potentiometer VR grounded at one end. Similarly, the green vacuum tube V_G includes the anode electrode energized by the source $B+$ through a resistor $R1_G$ and

15 connected through a parallel combination of a capacitor C_G and $R2_G$ to a grid electrode G_G of a green gun in the cathode-ray tube V_C to supply the color difference signal $G-Y$ to the grid electrode G_G with that end of the $C-R$ combination near to the grid electrode G_G being connected to a control resistor

20 $R3_G$ for controlling a color bias. Also the blue vacuum tube V_B has connected thereto the similar components designated by the same reference numerals designating the corresponding components connected to the red or green tube and having a suffix "B." The blue tube V_B is adapted to supply the color difference signal $B-Y$ to a grid electrode G_B of a blue gun in the cathode-ray tube V_C . The control resistors $R3_G$ and $R3_B$ are similarly connected to the slide on the potentiometer VR . Also all the color tubes include the respective cathode electrodes connected together to one end of a common cathode

25 resistor R_C grounded at the other end.

The three guns include the respective cathode electrodes applied with the luminance signal Y which, in turn, cooperates with the three color difference signals to produce a colored image on the phosphor screen of the tubes in the manner as well known in the art.

30 All the components as above described are of the conventional design and need not to be further described.

In FIG. 1 a dotted block represents a device for indicating the resonance in the above outlined color television receiver for correct tuning in accordance with the principles of the invention.

35 As shown within the block, the anode electrode of the last intermediate frequency amplifier stage V_1 is connected through a coupling capacitor C_1 to a frequency selective amplifier shown for example as being a pentode V_2 including a cathode electrode connected to a point of reference potential such as the ground potential through a resistor R_1 connected in parallel to a capacitor C_2 , a control grid electrode connected to the point of reference potential through a grid tank circuit T_1 and an anode electrode having an anode tank circuit T_2 connected between the same and a screen grid electrode which is, in turn, connected to a source of voltage through a resistor R_2 biased to the point of reference potential by a capacitor C_3 . As shown, both the tank circuits T_1 and T_2 are

40 preferably of the variable frequency type having, for example, a variable inductance and adapted to be turned to resonate at the video intermediate frequency. Thus the amplifier V_2 serves to selectively amplify the video intermediate frequency signal.

45 All the components as above described are of the conventional design and need not to be further described.

In FIG. 1 a dotted block represents a device for indicating the resonance in the above outlined color television receiver for correct tuning in accordance with the principles of the invention.

50 As shown within the block, the anode electrode of the last intermediate frequency amplifier stage V_1 is connected through a coupling capacitor C_1 to a frequency selective amplifier shown for example as being a pentode V_2 including a cathode electrode connected to a point of reference potential such as the ground potential through a resistor R_1 connected in parallel to a capacitor C_2 , a control grid electrode connected to the point of reference potential through a grid tank circuit T_1 and an anode electrode having an anode tank circuit T_2 connected between the same and a screen grid electrode which is, in turn, connected to a source of voltage through a resistor R_2 biased to the point of reference potential by a capacitor C_3 . As shown, both the tank circuits T_1 and T_2 are

55 preferably of the variable frequency type having, for example, a variable inductance and adapted to be turned to resonate at the video intermediate frequency. Thus the amplifier V_2 serves to selectively amplify the video intermediate frequency signal.

60 The output developed across the tank circuit T_2 from the frequency selective amplifier V_2 is inductively coupled to a semiconductor diode D where it is rectified into a negative unidirectional signal.

65 The output of the diode D is connected across a capacitor C_4 connected in parallel to a variable resistor R_3 . That junc-

70 The output developed across the tank circuit T_2 from the frequency selective amplifier V_2 is inductively coupled to a semiconductor diode D where it is rectified into a negative unidirectional signal.

The output of the diode D is connected across a capacitor C_4 connected in parallel to a variable resistor R_3 . That junc-

tion of the capacitor C_4 and resistor R_3 remote from the diode D is connected to the point of reference potential while the other junction thereof is connected to a resistor R_4 connected to the point of reference potential through a capacitor C_5 . The resistor R_3 and the capacitor C_4 form a low pass filter as do the resistor R_4 and the capacitor C_5 for the purpose of filtering out the high frequency portion of the rectified signal provided by the diode D.

The junction of the resistor R_4 and the capacitor C_5 is connected to a direct current amplifier shown as being a dual triode V_3-V_4 . Specifically that junction is connected to two grid electrodes of the dual triode V_3-V_4 . The triode includes two anode electrodes connected to the grid electrodes G_G and G_B of the cathode-ray tube V_C through resistors R_5 and R_6 respectively. Further the triode includes two cathode electrodes connected to the point of reference potential through a normally open switch S for the purpose as will be apparent hereinafter.

It is assumed that the three guns of the cathode-ray tube V_C are properly operating to develop successively the correctly colored images on the phosphor screen. Under the assumed condition, it is supposed that the potentials on the grid electrodes G_B and G_G of the blue and green guns greatly decrease beyond their properly operating points to cut off the electron beams from those guns. Then the successive images developed on the phosphor screen becomes red alone. Thus if means are provided for successively developing the correctly colored image only for correct tuning of a three gun tricolor television receiver then the particular televiewer can readily accomplish correct tuning thereof while he continues to view the color retention of the images.

More specifically, a potential at a point A connected to both the grid electrodes of the dual diode V_3-V_4 represents the output from the frequency selective amplifier V_2 after having been rectified by the diode D and varies with its frequency as shown at a resonance curve in FIG. 2 wherein the axis of ordinates designates the potential on the point A and the axis of abscissas designates its frequency. In other words, as a tuning knob involved is rotated after the receiver has been correctly tuned to resonate at the video intermediate frequency the potential at the point A will reach its maximum negative magnitude at the video intermediate frequency as shown in FIG. 2.

With the switch S manually closed to put the dual triode V_3-V_4 in its operating state, the variable resistor R_3 can be adjusted to cause the triode to become nonconducting for the potentials at the point A and adjacent the video intermediate frequency. That is, the triode can be put in its nonconducting state for the potentials at the point A negatively greater than those expressed by either of two points P_1 or P_2 on the resonance curve of FIG. 2 and adjacent to the valley point thereof. Under these circumstances, closing of the switch S does not affect the potentials at the grid electrodes G_G and G_B of the green and blue guns in the cathode-ray tubes V_C because the triode V_3-V_4 is not conducting to have no current flowing therethrough. This ensures that the cathode-ray tube V_C is maintained to produce the correctly colored images on its phosphor screen.

On the other hand, if the receiver is in its detuned state in which the potential at the point A is negatively less than that at the point P_1 or P_2 then the dual triode V_3-V_4 is in its conducting state in which a current flows through each of current paths traced from the source B+ through the resistors R_{1B} , R_{2B} and R_5 , the now conducting triode portion V_3 or through the resistors R_{1G} , R_{2G} and R_6 , the now conducting triode portion V_4 and hence to the point of reference potential through the closed switch S. As a result the potential on the green grid electrode G_G abruptly decreases due to voltage drops across the resistors R_{1G} and R_{2G} whereupon the green gun is driven into its cutoff state. Similarly voltage drops across the resistors R_{1B} and R_{2B} causes the blue gun to be cut off. Thus only the red gun is in its operative state to produce the red images in the entire area of the phosphor screen of the cathode-ray tube V_C .

This means that the receiver has not been correctly tuned. Thus by viewing the red images on the screen the particular televiewer can readily find of tuning-out of the receiver and will be required only to operate the associated tuning knob until the correctly colored images are produced on the screen.

Thus it will be appreciated that the changing of the receiver from its correctly tuned to its detuned state and vice versa causes a change in color of the images.

From the foregoing it will be appreciated that the objects of the invention have been accomplished by the provision of a device for indicating the resonance in a tricolor television receiver for correct tuning through the formation of correctly colored images on a phosphor screen of a three gun tricolor cathode-ray tube involve only upon correctly or substantially correctly tuning the receiver.

While the invention has been illustrated and described in conjunction with a single preferred embodiment thereof it is to be understood that numerous changes in the details of construction and the combination and arrangement may be resorted to without departing from the spirit and scope of the invention. For example, the receiver may produce images having the red color alone for correct tuning. In the latter case diode D has its polarity reversed from that illustrated and the dual triode is adapted to be conducting for the potentials at the point A negatively greater than the potential expressed by the point P_1 or P_2 on the resonance curve shown in FIG. 2. Also instead of the red images, the green or blue images may be produced for correct tuning or detuning. Further, transistors may substitute the vacuum tubes illustrated.

What I claim is:

1. In a tricolor television receiver including tuning means and a three gun tricolor cathode-ray tube having a phosphor screen, an indication device for indicating the resonance in the receiver for correct tuning, comprising narrow band detector means for sensing correct tuning, and automatic color varying means connected to said detector means for causing a variation in color of images produced on the phosphor screen in accordance with the transition of the receiver from its correct tuned to its detuned state and vice versa.

2. An indication device as claimed in claim 1 wherein said color varying means includes means to control the grid electrodes of the cathode-ray tube so as to produce on the entire area of the phosphor screen images having only a selected one of the three primary colors for correct tuning.

3. An indication device as claimed in claim 1 wherein said color varying means includes means to control the grid electrodes of the cathode-ray tube so as to produce on the entire area of the phosphor screen images having only a selected one of the three primary colors for detuning.

4. An indication device as claimed in claim 1, in which said narrow band detector comprises frequency selective amplifier means having the video IF signal of said receiver connected thereto for providing an output whose magnitude is controlled by the tuning means and means for supplying the output from the amplifier means to selected two of three grid electrodes of the cathode-ray tube to permit the images having only a single color associated with the remaining grid electrode to appear on the entire area of the phosphor screen until correct tuning is achieved.

5. In a tricolor television receiver including tuning means and a tricolor cathode-ray tube having a phosphor screen, an improved indicator device for indicating the correct video IF signal in the receiver for correct tuning, comprising, narrow frequency band detector means for detecting the correct video IF signal, and means connected to said detector means for causing a variation in color of images produced on the phosphor screen in accordance with the transition of the receiver from its detuned state to its correctly tuned state.

6. The invention as set forth in claim 5, in which said narrow frequency band detector means comprises amplifier and rectifier means having said video IF signal coupled thereto, and said means for causing a color variation comprises dual bias control means connected between said rectifier means and

two color grid electrodes of said cathode-ray tube, wherein said dual bias control means biases said two color grids to cut off until said receiver is correctly tuned, whereupon said dual

bias control means is biased by said rectifier means to an inactive state.
